UNITED STATES PATENT OFFICE.

RUDOLF PFAFFENBACH, OF LEIPSIC, AND HERMANN MÜLLER, OF LEIPSIC-GOHLIS, GERMANY.

SWITCH FOR SUSPENDED ELECTRIC RAILWAYS.

SPECIFICATION forming part of Letters Patent No. 787,856, dated April 18, 1905.

Original application filed January 13, 1904, Serial No. 188,876. Divided and this application filed October 29, 1904. Serial No. 230,495.

To all whom it may concern:

Be it known that we, RUDOLF PFAFFENBACH, director, residing at 34 Pfaffendorferstrasse, Leipsic, and HERMANN MÜLLER, engineer, residing at 8 Ulanenstrasse, Leipsic-Gohlis, Germany, subjects of the German Emperor, have jointly invented new and useful Improvements in and Relating to Switches of Suspended Electric Railways; and we do hereby declare the following to be a full, clear, and exact description of our invention, such as will enable others skilled in the art to which it appertains to make and use the same.

The present invention relates to suspended electric railways wherein the cars run on rails supported above the ground and carry the load in a suspended carrier and are driven by one or more electromotors mounted on the car which receive their current from a conductor extending along the line.

The present application is a division of a prior application filed by us January 13, 1904, Serial No. 188,876.

In order that with suspended railways of the kind in question there shall be no liability of the car falling on account of misplacement of the switches, safety devices are provided by the present invention which consist in electrically insulating the portion of the conductor beyond the switch-rail from the remainder of the conductor when the switch-rail is open, whereas by closing the switch-rail a contact device is actuated which connects the insulated portion with the source of electricity. Consequently with this device when the switch-rail is open the car is brought to rest when on the insulated dead portion, and therefore cannot fall down. Obviously the dead portion of the conductor must be prolonged sufficiently beyond the end of the switch-rail in order that the car when the switch is open shall not run onto it by its onward momentum.

In the accompanying drawings, Figure 1 shows a horizontal portion of the track with which there is a branch connection. Fig. 2 is a plan of the same, showing a safety device, the branch being shown with the switch-rail

open. Fig. 3 is a view corresponding to Fig. 2, in which the switch-rail is shown closed. 50

In Figs. 1 and 2, *a* indicates the cars; *b*, the carriers; *c*, the loads; *d*, the rails; *e*, the overhead conductors, and *f* the current-collector.

In Figs. 2 and 3, *d* represents the continuous rail, and *d'* the branch rail with the switch-rail *p*. Above the track are situated the conductor-wires *e*, *e'*, and *q*. For the purpose of clearness they are shown drawn not above the middle of the rails. While the conductors *e* and *e'* are electrically connected with the source of current the portion *q* of the conductor is insulated from the remainder by insulators *r* and *s*. An electrical connection is made between the portions *q* and the conductor *e* by the insulated conductors *t* *u* 65 through the electric switch *v*, which is secured to the rails *d* opposite the switch-rail *p*. The electric switch *v* is actuated by the pin *w*, which is guided in a sleeve *x*, passing through the rail and terminating in a head, 70 beneath which is a plate-spring *y*, the latter tending constantly to open the electric switch *v*, as shown in Fig. 2. The conductor *q* is thereby rendered dead, so that an electric car proceeding from *e'* to *d'* will come to rest on 75 the dead section *q*.

When the switch-rail *p* is closed, as shown in Fig. 3, the rail *p* will press against the pin *w* and forcing it inward against the action of the spring *y* will close the electric switch *v* and connect the conductor *q* with the source of current. A car can then traverse the rails *d'* and *p* and pass to the track *d*.

What we claim is—

1. In an elevated railway on which cars are suspended and driven by electromotors thereon, the combination with a main line, of a branch connection having a switch-rail, an electrical conductor along the main line and the branch connection, and means for electrically insulating the portion of the conductor situated along the switch-rail and the adjoining portion of the branch connection from the remainder of the conductor by the switch-rail being opened, and for reconnecting the insulated portion with the source of electricity by

the closure of the switch-rail, substantially as described and for the purpose set forth.

2. In an elevated railway from which electric-motor cars are suspended, the combination with a main line, of a branch line having a switch-rail, an electric conductor extending along the main line and branch connection and having a normally dead portion corresponding to the switch-rail, and an electric switch normally open and interposed between the live and dead portions of the conductor,

the lever of the electric switch being located in the path of closing movement of the switch-rail; substantially as described and for the purpose set forth.

In witness whereof we have hereunto set our hands in presence of two witnesses.

RUDOLF PFAFFENBACH.
HERMANN MÜLLER.
